UNITED STATES PATENT OFFICE.

JOHN ROCKE, OF MEADOWS, ILLINOIS.

DRIVING MECHANISM AND SUPPORT THEREFOR.

1,188,207.

Specification of Letters Patent. Patented June 20, 1916.

Application filed July 28, 1911. Serial No. 641,066.

To all whom it may concern:

Be it known that I, JOHN ROCKE, a citizen of the United States, residing at Meadows, in the county of McLean and State 5 of Illinois, have invented a new and useful Driving Mechanism and Support Therefor, of which the following is a specification.

The present invention aims to provide a washing machine having means for simultaneously operating a wringer and the agitating mechanism of the washing machine.

A further object of the invention is to provide a structure of the class described having means for shifting a wringer from a washing machine to a rinsing tub, means being provided for operating the wringer when the wringer is adjacent the tub, or adjacent the washing machine.

A further object of the invention is to provide a means for reversing the wringer, and for rendering the wringer inoperative, while the agitating mechanism of the washing machine is in operation.

With the foregoing and other objects in view which will appear as the description proceeds, the invention resides in the combination and arrangement of parts and in the details of construction hereinafter described and claimed, it being understood 30 that changes in the precise embodiment of invention herein disclosed can be made within the scope of what is claimed without departing from the spirit of the invention.

In the drawings.—Figure 1 shows the invention in side elevation, parts being sectioned; Fig. 2 is a top plan; Fig. 3 is a transverse vertical section upon the line A—B of Fig. 1; Fig. 4 is a top plan of the main frame of the machine, parts thereof being removed, in order that the gearing may more clearly appear; Fig. 5 is a sectional elevation of one of the pedals whereby the clutch is shifted; and Fig. 6 is a similar view showing another of the clutch shifting pedals.

In carrying out the mechanism there is provided a main frame 1, of any desired form, the frame 1 supporting adjacent its ends, a receptacle 2, constituting a part of a washing machine, and a receptacle 3, constituting a rinsing tub.

Disposed transversely of the main frame 1, and journaled for rotation therein, is a drive shaft 4, carrying at one end a pulley 5 or suitable means whereby the drive shaft may be rotated. Disposed at right angles

to the drive shaft 4 is a supplemental shaft 6, journaled in one end of the main frame 1, and in a suitable frame-supported hanger 7. The drive shaft 4 is operatively connected 60 with the supplemental shaft 6 through the instrumentality of the intermeshing beveled pinions 8. One end of the supplemental shaft 6 protrudes beyond one end of the main frame 1, the protruding end of the supplemental shaft 6 carrying a sprocket wheel 9, about which is trained a sprocket chain 10, engaged with a sprocket wheel 11 secured to the shaft 12, located adjacent the upper edge of the receptacle 2, and journaled for rotation in a casing 14 housing the sprocket chain 11. The casing 14 is secured to the main frame 1, and may, if desired, be secured to the receptacle 2 of the washing machine. 75

Secured to the shaft 12 is a pinion 15, adapted to mesh into a pinion 16, secured to one end of a shaft 17, journaled for rotation in bearings 18 carried by the cover 19 of the washing machine receptacle 2. The 80 cover 19 is hinged to the receptacle 2 as shown at 20, and its free edge is latched to the receptacle, as shown at 21. When the cover 19 is in open position, the pinions 16 and 15 will be out of mesh, but when the cover 19 is in closed position, the pinions 15 and 16 will mesh together. Therefore, when the cover 19 is in open position, the shaft 17 will not be driven.

At its inner end, the shaft 17 is connected 90 by beveled pinions 22 with the shaft 23 of the washing machine, the shaft 23 representing the agitating mechanism of the washer.

The numeral 24 denotes, conventionally, 95 mechanism for reversing the rotation of the shaft 23 automatically. This reversing mechanism 24 constitutes no part of the present invention, and it is, therefore, alluded to but briefly.

Disposed transversely of the frame 1 and journaled for rotation therein, adjacent the drive shaft 4, is an auxiliary shaft 25. The ends of the auxiliary shaft 25 protrude beyond the side walls of the main frame 1, 105 and upon the protruding ends of the auxiliary shaft, are pivoted the lower ends of arms 26, connected by a transverse frame 27, supporting a wringer 28, one of the roll shafts of the wringer being denoted by the 110 numeral 29. The roll shaft 29 carries at one end a sprocket 30, about which is

trained a sprocket chain 31, carried over the sprocket wheel 32, carried by one end of the auxiliary shaft 25. Fixed to and rising from one end of the main frame 1, adjacent the outer edge of the rinsing tub 3, is a standard 33. The frame 27 is equipped upon its lower edge with a T-shaped head 34, adapted to fit over the upper end of the standard 33, as clearly shown in solid line in Fig. 1. The wringer-supporting frame, comprising the members 26 and 27 may be moved pivotally upon the shaft 25, so that the T-shaped head 34 will engage with an angle bracket 35, secure to the receptacle 2 of the washing machine. The construction, therefore, is such that the wringer 28 may be positioned adjacent the rinsing tub 3, or adjacent the washing machine receptacle 2, as Fig. 1 will clearly indicate.

Mechanism is provided for operatively connecting the auxiliary shaft 25 with the drive shaft 4. This mechanism includes a pinion 36, fixed upon the auxiliary shaft 25, the pinion 36 meshing into a pinion 37 which is loose upon the drive shaft 4. The auxiliary shaft 25 is further connected with the shaft 4 through the instrumentality of a pinion 38 fixed upon the auxiliary shaft 25, the pinion 38 meshing into an idle pinion 39, journaled for rotation upon the main frame 1, the pinion 39 meshing into a pinion 40 which is loose upon the drive shaft 4. Slidably mounted upon the drive shaft 4, between the pinions 37 and 40, is a clutch 41, adapted to interengage successively, with the elements 41^a, on the pinions 37 and 40. When the clutch is engaged with the pinion 37, the pinion 37 will be locked for rotation with the shaft 4, and when the clutch 41 is engaged with the pinion 40, the pinion 40 will be locked for engagement with the shaft 4. When the clutch 41 stands in a position intermediate the pinions 37 and 40, the shaft 4 will rotate freely, without rotating the auxiliary shaft 25.

A means is provided for shifting the clutch 41. This means may be of any desired construction. If preferred, the main frame 1 may carry a pair of spaced hangers 42, in which rock shafts 43 and 44 are journaled for rotation. The frame 1 also carries a brace 45 extended longitudinally of the frame, as shown in Fig. 1. This brace 45 serves as a support for pedals 46 and 47, the pedal 46 being fulcrumed at one end upon the brace 45, and the pedal 47 being fulcrumed intermediate its ends upon the brace, as clearly appearing in Figs. 5 and 6. The clutch 41 rotates in a collar 48, connected loosely with a rigid arm 49 upon the shaft 43, the shaft 43 having another rigid arm 50, connected by means of a link 51, with the inner end of the pedal 47. The collar 48 is loosely connected to an arm 53, outstanding from the shaft 44, the shaft 44

having another angularly disposed arm 54, connected by a link 55, with the intermediate portion of the pedal 46. As Fig. 1 will serve to show, a pair of pedals 46-47 is located adjacent the rinsing tub 3, and another pair of pedals, similarly constructed, are located adjacent the washing machine receptacle 2, so that the clutch 41 may be operated from either end of the structure.

The operation of the device is as follows: 75 When the drive shaft 4 is rotated through the instrumentality of the pulley 5 or otherwise, the beveled pinions 8 will cause a rotation of the supplemental shaft 6, the sprocket wheel 9 of which will actuate the sprocket chain 10, the sprocket chain 10, through the medium of the sprocket wheel 11, causing a rotation of the shaft 12, the shaft 12 rotating the pinion 15, the pinion 15 meshing into the pinion 16 and causing 80 a rotation of the shaft 17, the intermeshing beveled pinions 22 serving to operate the agitating mechanism 23 of the washing machine. As hereinbefore set forth, when the cover 19 of the washing machine is in open 85 position, the pinions 15 and 16 will be out of mesh, and consequently the agitating mechanism of the washing machine will not be operated.

By noting Figs. 5 and 6, it will be seen 95 that when the pedal 46 is pressed, the collar 48, and consequently the clutch 41, will be moved in one direction; whereas, when the pedal 47 is depressed, the collar 48, and consequently the clutch 41, will be moved in 100 an opposite direction. When the clutch 41 is engaged with the pinion 37, the pinion 37 will be held for rotation with the drive shaft 4, and the pinion 37, meshing into the pinion 36, will rotate the auxiliary shaft 105 25 in one direction. On the other hand, when the clutch 41 is in engagement with the pinion 40, the pinion 40 will be rotated, the pinion 40 meshing into the idle pinion 39, and the pinion 39 meshing into the pinion 110 38. The latter pinion, being secured to the auxiliary shaft 25, will cause a reverse rotation of the shaft 25. When the clutch 41 stands in an intermediate position between the pinions 40 and 37, the auxiliary 115 shaft 25 will remain at rest, because the pinions 37 and 40 are both loose upon the drive shaft 4. When the auxiliary shaft 25 is rotated in either direction, through the mechanism hereinbefore set forth, the sprocket wheel 32 upon one end of the auxiliary shaft 25, will actuate the chain 31, the chain 31, through the medium of the sprocket 30, rotating the roller shaft 29 of the wringer.

The wringer-supporting frame, comprising the elements 26 and 27 may, as hereinbefore set forth, be swung from engagement with the standard 33, or into engagement with bracket 35, thereby moving the wringer 120 125 130

29 from operative position with respect to the rinsing tub 3, into operative relation with respect to the receptacle 2 of the washing machine.

5 Having thus described the invention, what I claim as new and desire to protect by Letters Patent is:—

1. A device of the class described comprising a horizontally disposed main frame; 10 a horizontal shaft journaled for rotation in the main frame; a manually movable supplemental frame pivotally mounted upon the shaft, the supplemental frame being movable in a fixed vertical plane; a machine carried by the free, upper end of the supplemental frame; means for operatively connecting the machine with the shaft; and spaced supports carried by the main frame, the supports being engageable by the supplemental frame, when the supplemental frame is manually moved, to dispose the machine in horizontally spaced positions. 15

2. A device of the class described comprising a horizontally disposed main frame; 20 a horizontal shaft journaled for rotation in the frame, and terminally protruding beyond the sides of the frame; a manually movable supplemental frame pivotally connected with the protruding ends of the shaft, upon the outside of the main frame, the supplemental frame being movable in a fixed vertical plane; a machine carried by the free, upper end of the supplemental frame; means connected with one of the 25 protruding ends of the shaft, for operatively uniting the machine with the shaft; and spaced supports carried by the main frame, the supports being engageable by the supplemental frame, to dispose the machine in 30 spaced horizontal positions, when the supplemental frame is manually moved upon the shaft. 35

3. A device of the class described comprising a horizontally disposed main frame; 40 a horizontal shaft journaled for rotation in the frame, and terminally protruding beyond the sides of the frame; a manually operable supplemental frame pivotally supported upon the protruding ends of the shaft, beyond the sides of the main frame, the supplemental frame being movable in a fixed vertical plane; a machine carried by the free upper end of the supplemental frame; a belt trained about one of the protruding ends of the shaft and operatively connected with the machine; spaced supports fixed to and rising vertically from the main frame; the machine including a T-shaped head, adapted to engage with the 45 supports successively, to dispose the machine in horizontally spaced positions. 50

4. A device of the class described comprising a horizontally disposed main frame; a vertically positioned, primary machine 55 fixed to the main frame; a vertical support

carried by the main frame and spaced from the primary machine; a horizontally disposed drive shaft journaled in the main frame; a horizontal auxiliary shaft journaled for rotation in the main frame, parallel to the drive shaft; gear trains connecting the shafts, the gear trains including pinions loose upon the drive shaft, and one train including an idler; a clutch operable upon the drive shaft to connect the loose pinions alternately with the drive shaft; means for operatively connecting the primary machine with the drive shaft; a manually operable supplemental frame mounted for swinging movement in a fixed vertical plane upon the auxiliary shaft and adapted to engage the primary machine and the support, when the supplemental frame is manually moved; a secondary machine carried by the free, upper end of the supplemental frame, and adapted to be positioned adjacent the support and adjacent the primary machine, when the supplemental frame is manually moved; and means for operatively connecting the secondary machine with the auxiliary shaft. 70 75 80 85

5. In a machine of the character described, a main frame, a supplemental frame pivotally mounted thereon, an operating means mounted on said supplemental frame, 90 said supplemental frame being adapted to be moved to different angles relative to a perpendicular line through its pivot to position said operating means at different positions relative to said main frame so as to adapt said operating means to operate on the same work during different stages of its treatment, a power driven element, and connections between said power driven element and said operating means, said connections including reversing means so arranged as to drive said operating means in its adjusted position in either direction, as desired. 100

6. In a machine of the character described, a main frame, a supplemental 110 frame pivotally mounted thereon, an operating means mounted on said supplemental frame, said supplemental frame being adapted to be moved to positions on either side of a perpendicular line through its 115 pivot to position said operating means at different positions relative to said main frame so as to adapt said operating means to operate on the same work during different stages of its treatment, a power driven element, and connections between said power driven element and said operating means, said connections including reversing means 120 so arranged as to drive said operating means in its adjusted positions in either direction, 125 as desired.

7. In combination, a support, a member pivoted thereto and uprising from its pivot, a mechanism mounted on the outer portion of said member, a drive-wheel having its 130

axis of rotation substantially coincident with the axis of the pivot of the member, means to operate said mechanism from said drive-wheel, and means adapted for reversing the direction of rotation of said mechanism and for interrupting said rotation.

8. In a device of the character described, in combination, a support, a driving shaft, reversible means for operating said shaft, reversible actuating gears loosely mounted on said shaft, means for alternately clutching said gears to said shaft, a supplemental support pivotally mounted on the main support and swingable across the axis of said pivots, and 15 a mechanism on said swingable support adapted to be operated by said gears.

9. In a machine of the character described, a main frame, a supplemental frame pivotally mounted thereon, an operating means mounted on said supplemental frame, actuating means for said operating means, 20 said actuating means including a power

driven element and a plurality of rotary members and connections between said rotary members and said operating means, 25 said connections being so arranged that when one of said rotary members is driven directly by said power driven element, said operating means will be driven in one direction and when the other of said rotary members is driven directly by said power driven element, said operating means will be driven in the opposite direction, said power driven element being normally out of operative relation with said rotary members and being 30 adapted to be placed in operative relation with either of said rotary members.

In testimony that I claim the foregoing as my own, I have hereto affixed my signature in the presence of two witnesses.

JOHN ROCKE.
